UNITED STATES PATENT OFFICE.

FRANK C. MEDICK, OF COLUMBUS, OHIO.

DESIGN FOR A PHOTOGRAPH MOUNT.

Application filed May 17, 1926. Serial No. 17,754. Term of patent 14 years.

To all whom it may concern:

Be it known that I, FRANK C. MEDICK, a citizen of the United States, residing at Columbus, in the county of Franklin and State of Ohio, have invented a new, original, and ornamental Design for Photograph Mounts, of which the following is a specification, reference being had to the accompanying drawing, forming part thereof.

The figure is a plan view of a photograph mount, showing my new design.

I claim:

The ornamental design for a photograph mount, as shown.

FRANK C. MEDICK.
